[57] CLAIM

The ornamental design for bottle, as shown and described.

DESCRIPTION

FIG. 1 is a front elevation of a bottle showing my new design;

FIG. 2 is a left side elevation thereof, the right side is a mirror image thereto;

FIG. 3 is a rear elevation thereof; and

FIG. 4 is a top plan view thereof.

The bottom of the bottle is unornamented.

FIG. 1

FIG. 2

FIG. 3

FIG. 4
